CLAIM

The ornamental design for a notepad holder and calculator, as shown and described.

DESCRIPTION

FIG. 1 is a perspective view of the notepad holder and calculator in the closed position.

FIG. 2 is a top view of the notepad holder and calculator in closed position.

FIG. 3 is a bottom view of the notepad holder and calculator in closed position.

FIG. 4 is a left side view of the notepad holder and calculator in closed position.

FIG. 5 is a right side view of the notepad holder and calculator in closed position.

FIG. 6 is a back side view of the notepad holder and calculator in closed position.

FIG. 7 is a front side view of the notepad holder and calculator in closed position; and,

FIG. 8 is a top view of the notepad holder and calculator in open position.

The broken lines shown in FIGS. 1, 2, 4, 5, 7, and 8 are included for the purpose of illustrating environment and form no part of the claimed design.
